UNITED STATES PATENT OFFICE.

CHARLES A. DURGIN, OF EAST ANDOVER, NEW HAMPSHIRE.

DESIGN FOR A CORNER-PIECE FOR ROOMS.

Specification forming part of Design No. 5,200, dated August 15, 1871.

To all whom it may concern:

Be it known that I, CHARLES A. DURGIN, of East Andover, in the county of Merrimack and State of New Hampshire, have produced and invented a new and original Design for a Corner-Piece for Rooms, &c., to prevent the accumulation of dirt, of which the following is a specification:

My invention consists in making a triangular corner-piece for rooms, &c., of corrugated sheet metal stamped or pressed up into the form shown in the accompanying drawing, so that it can be readily secured in place in the corner of a room or other place; and it has for its object to prevent the accumulation of dirt.

The accompanying drawing shows the form of my corner-piece and the mode of its application. It is made of triangular shape, with corrugations pressed or struck up in it, and it is provided with a hole to receive the screws by which it is held in place.

I claim—

The design for a corner-piece for rooms, stairs, &c., of corrugated sheet metal, substantially as shown in the accompanying drawing.

C. A. DURGIN.
